E. MERRITT COLE, OF SOUTHBRIDGE, MASSACHUSETTS.

Letters Patent No. 72,978, dated January 7, 1868.

IMPROVEMENT IN EYE-GLASSES.

The Schedule referred to in these Letters Patent and making part of the same.

TO ALL PERSONS TO WHOM THESE PRESENTS SHALL COME:

Be it known that I, E. MERRITT COLE, of Southbridge, in the county of Worcester, and State of Massachusetts, have invented a new and useful Improvement in Spectacles or Eye-Glasses; and I do hereby declare the same to be fully described in the following specification, and represented in the accompanying drawings, of which—

Figure 1 is a top view, and

Figure 2 a side elevation of one of the eye-glass frames, and the bow thereof of a pair of spectacles.

Figure 3 is a horizontal section, and

Figure 4 a vertical section of the same.

Figure 5 is a front view of the frame as it appears when opened apart ready to receive a lens or glass.

All of the said figures are drawn on an enlarged scale.

In such drawings, A denotes the glass or lens-frame, and B the bow, the two being hinged together, and the bow being held in place by a screw, *a*, going through the two lips *b c* projecting from, and forming part of the frame. The lower or joint part of the bow is arranged in a socket made in one of the lips. In carrying out my improvement, I form in one of the said lips, from its inner edge, a mortise or socket, *d*, and I extend from the inner surface of the other lip a small tenon or projection, *e*, to enter and fit closely into such mortise, when the lips are closed and held together by the joint-screw. This tenon and mortise render unnecessary any auxiliary screw to go through the two lips in order to prevent the working of the bow from twisting or moving the parts of the frame, so as to either break or disengage a lens or glass when in such frame. An auxiliary screw, when used for such purpose, is liable to work loose and be lost out of the lips, and requires the lips to be very much larger than they need be when they are provided with my invention or improvement. With the latter the tenon and mortise are completely out of sight when the lips are closed, and there is no danger of the tenon being lost, it being permanently fixed to the lip.

What, therefore, I claim, is—

The arrangement and application of the tenon and mortise with the lips, and with respect to the joint-screw or pin of the spectacle or eye-glass frame, substantially as specified.

E. MERRITT COLE.
